BRUSH

Conrad Jobst, Toledo, Ohio, assignor to The Toledo Automatic Brush Machine Company, Toledo, Ohio, a corporation of Ohio

Application January 26, 1942, Serial No. 428,289

3 Claims. (Cl. 15—190)

In the manufacture of brushes employing bristle tufts, it is the common practice to form these tufts by bending the bristles double about a transversely extending anchor and to then simultaneously drive the anchor and bristles into a bored back to set the tuft. Anchors have been made of various materials, but to secure permanency and to avoid discoloration, it has been the practice to employ a non-corrodible metal such, for instance, as stainless steel. This will form an anchor which, where the brush is used for the purpose for which it is designed, will remain unchanged throughout its life.

An essential element of stainless steel, as well as other non-corrodible alloys, is the metal chromium. This has heretofore been available, but under present conditions within the United States, its use may be restricted to such industries as are engaged in the preparedness program. Under such conditions, it may be difficult or impossible for brush manufacturers to obtain non-corrodible metal for forming tuft anchors.

It is the object of the invention to obtain a satisfactory tuft anchor which does not require the use of stainless steel or other noncorrodible metal.

It is a further object to obtain an anchor which has additional advantageous characteristics for use in forming brushes, particularly brushes of that type in which the tufts are set in a back of transparent material.

With these objects in view, the invention consists in the construction of a tuft anchor; further, in the method of forming the same; and still further, in the construction of brush employing such tuft anchors as hereinafter set forth.

In the drawing:

Fig. 1 is an enlarged plan view of a portion of a toothbrush of my improved construction, viewed from the back;

Fig. 2 is a side elevation thereof;

Fig. 3 is an enlarged cross section of a round enameled wire;

Fig. 4 is an enlarged cross section of the wire after flattening the same preparatory to forming the anchors thereof; and

Fig. 5 is an enlarged cross section through a portion of a bored back, showing a tuft set therein.

In the present state of the art, wire formed of certain copper alloys has been provided with an enamel coating, primarily designed for electrical insulation. This wire is usually of circular cross section, and the enamel completely envelops its outer surface. I have discovered that such enameled

wire can be flattened by suitable means as by rolls, and without injury to its enamel coating, this being sufficiently elastic to compensate for the increased length of perimeter. I have also discovered that such flattened enameled wire may be substituted for the stainless steel or other non-corrodible metal heretofore used in tuft forming and setting mechanisms; further, that the anchors severed from the wire, when driven into the brush back, will be protected from corrosion. This is for the reason that the only portions of the anchor that are not covered by the enamel are the opposite ends, and these being embedded in the brush back, are protected thereby.

During recent years, certain synthetic materials have been used for forming brush backs, and some of these are transparent, so that the tufts and anchors are visible therethrough. With my improved construction of anchor, the enameled surface may be formed of any desired color and will give a distinctive appearance to the brush. While the greater portion of the anchor is enveloped by the bristles of the tuft, the latter are also frequently formed of synthetic transparent material, and consequently the color of the enamel will be visible through the back.

As specifically illustrated, A is a metallic wire of copper alloy or other suitable metal, having the desired physical characteristics. B is the enveloping coating of enamel. C is the flattened wire which has the enamel coating B' still intact and completely covering the surface. D is the brush back, E is the tuft set in a bore in said back, and F is the anchor cut from the wire C and having its opposite end embedded in the walls of the bore. As shown in Figs. 1 and 2, the portions G of the anchor which project beyond the bristles of the tuft are clearly visible through the transparent back and to a lesser extent the portions H which are covered by the bristles. This would impart to the brush a distinctive appearance due to the color of the enamel.

The specific composition of the enamel coating of the wire is not essential to my invention, provided that it possesses the necessary ductility to stretch over the increased perimeter of the cross section. I have found, however, that organic coating material such as described in Patents No. 2,085,995 to W. I. Patnode et al., July 6, 1937; and No. 2,191,581 to P. Nowak et al., February 27, 1940, is suitable for the purpose. I have also discovered that with such materials, during the process of driving the anchor into a

brush back of synthetic material, the enamel coating will weld to the synthetic material of the back, thereby insuring complete coverage and also increasing the strength of the bond. This welding effect is doubtless due to the fact that in brush machines the anchors are driven into the brush backs at an extremely high rate of speed. Thus, the frictionally generated heat is sufficient to soften the contacting surfaces of the enamel and the brush back so that they 10

will weld to each other.

2. In a method of forming brushes, the steps of rolling a metallic wire provided with a non-metallic insulating elastic coating to flatten the same into an oblong cross section, thereby stretching the coating to completely cover the perimeter, severing the flattened wire into anchor lengths, and driving each anchor with a tuft into a bored brush back, thereby embedding the uncoated ends of the anchor in said back.

3. In a brush, a back formed of synthetic material, a tuft set in said back, and an anchor for said tuft having a protective non-metallic coating surrounding the same, the opposite ends of said coating being welded to the material of said back.

What I claim as my invention is:

1. The combination with a brush back provided with a tuft receiving bore, of a tuft set in said bore, and an anchor for said tuft having all but the ends of its surface coated with enamel, said ends being embedded in the back to protect the same from corrosion.

CONRAD JOBST.
